(57) **CLAIM**

The ornamental design for a wireless wall charger, as shown and described.

DESCRIPTION

FIG. 1 shows a perspective view of a wireless wall charger; FIG. 2 shows a front view of the wireless wall charger; FIG. 3 shows a rear view of the wireless wall charger; FIG. 4 shows a right side view of the wireless wall charger; FIG. 5 shows a left side view of the wireless wall charger; FIG. 6 shows a top plan view of the wireless wall charger; and, FIG. 7 shows a bottom plan view of the wireless wall charger.

The shade lines in the Figures show contour and not surface ornamentation.

The broken lines shown in the Figures show portions of the wireless wall charger that form no part of the claimed design.

1 Claim, 5 Drawing Sheets
